UNITED STATES PATENT OFFICE.

JOHN L. FAY, OF ST. LOUIS, MISSOURI.

GROUND-ANCHOR.

1,103,185.

Specification of Letters Patent. Patented July 14, 1914.

Application filed February 24, 1913. Serial No. 750,231.

To all whom it may concern:

Be it known that I, JOHN L. FAY, a citizen of the United States, residing at city of St. Louis, State of Missouri, have invented a certain new and useful Improvement in Ground-Anchors, of which the following is a full, clear, and exact description, such as will enable others skilled in the art to which it appertains to make and use the same, reference being had to the accompanying drawings, forming part of this specification, in which—

Figure 1 is a side elevational view partly in section of my improved ground anchor. Fig. 2 is a top plan view partly in section, of the same.

This invention relates to new and useful improvements in ground anchors for use in connection with guy ropes or cables, the object being to make a device of the character described which is simple, cheap and effective.

In the drawings, 1 indicates the rod to which the guy rope or cable is attached, 25 said rod extending to or above the ground. The anchor is buried in the ground usually by digging a hole and then tamping stones or earth around the anchor and filling the hole.

30 2 is the anchor proper which is preferably in the form of the frustum of a cone. The side walls of the anchor are provided with vertically disposed slots, preferably arranged in parallel pairs.

35 3 is a fluke preferably tapering to a point at its outer edge and being curved slightly outward to increase its holding powers. There may be a plurality of these flukes disposed around the anchor, each fluke being 40 held in position by the bail wire 4 passing through the slots as shown.

In practice, the hole made to receive the anchor is usually only slightly larger than the base of the anchor and consequently 45 when the anchor is introduced into the hole,

the flukes may be raised so that their outer edges will be within the lines of the base of the anchor. If desired, the flukes can be held so elevated by tying them up with a light string. When the anchor is introduced into the hole, the flukes are forced downwardly by the tamping tool, such action also forcing the flukes outwardly into the side walls of the hole whereby their holding powers are greatly increased. 50 Should the flukes become broken by such tamping action, or if the wires should rust away, the holding powers of the flukes will still be retained by virtue of the wedging action of the conical shape of the anchor. 55

While it is preferable to use stones as a top bedding and tamping the anchor in position, it is not absolutely necessary to do so with my present form of anchor, because the flukes coöperating with the conical anchor, though loose, will act practically the same as stones tamped around the anchor. 65

What I claim is:

1. A ground anchor comprising a conical base having pairs of vertically disposed 70 slots, and a plurality of flukes provided with bail wires passing through said slots whereby said flukes are capable of movement upon said base.

2. In a ground anchor the combination 75 with a base, the lower end of which is substantially larger in diameter than the upper end, said base being provided with vertically disposed slots, and a plurality of flukes radially disposed around the base, parts of 80 which flukes are loosely mounted in the slots whereby said flukes are pivotally and slidably connected to said base.

In testimony whereof I hereunto affix my signature in the presence of two witnesses, 85 this 4th day of February, 1913.

JOHN L. FAY.
